UNITED STATES PATENT OFFICE

FRANK WOLF, OF NEW YORK, N. Y.

STAND OR HOLDER FOR CONTAINERS

Application filed December 24, 1928. Serial No. 328,104.

This invention relates to improvements in stands or holders for containers; especially containers in the form of collapsible tubes to receive shaving and dental preparations, 5 salves, ointments and other substances.

An object of the invention is to provide a stand or holder comprising movable parts or legs, mounted at their lower ends, for so engaging a collapsible tube that the latter 10 can be readily put into the holder and supported thereby while the tube is in use, the stand being open so that the tube is exposed for handling to squeeze out the contents.

Another object of the invention is to provide a stand for a collapsible tube constructed to grip the tube and having a base to which a pair of upright legs are pivotally secured. The tube is mounted between these legs and an accessory member is attached to the tube 20 to retain the legs in the required supporting position.

A further object is to provide a stand with legs that can be adjusted to suit tubes of various lengths.

25 The nature of the invention is fully set forth in the following description, taken with the drawings which show a preferred construction in which the invention is embodied. But the disclosure is illustrative 30 only, and changes in the shape, size and arrangement of the various parts of the stand can be made without departing from the principle of the invention or exceeding the scope and meaning of the appended claims.

35 On the drawings,

Figure 1 is a side view showing the stand by itself;

Figure 2 is a side view showing the stand holding a tube in position;

40 Figure 3 is a side view seen from the left of Figure 2;

Figure 4 shows a detail;

Figure 5 is an inner side view of the upper end of one of the legs of the holder;

45 Figure 6 is a section on line 6—6 of Figure 5;

Figure 7 is a bottom view of the base of the stand;

50 Figure 8 is a section on line 8—8 of Figure 7; and

Figure 9 is a section on line 9—9 of Figure 7.

On the drawings the same numerals identify the same parts throughout.

The numeral 1 indicates a base to which 55 are pivotally connected legs 2, which engage the tube just below the top thereof at their upper ends. At 3 is shown an accessory in the form of a cover which may encircle the tops of the legs 2 and the top 4 of the tube; 60 which is indicated at T. This cover holds the legs in position to engage firmly with the tube, so that the latter is kept in place. The tube has a relatively soft collapsible body with a comparatively rigid top 4 having 65 a central outlet nipple 20 and a surrounding bead-flange 11 at its periphery.

The base 1 is hollow on the underside and carries a transverse bar 5, which is rigid with the base. At the ends of this bar the base 70 has openings 6, and each of the legs has separated lugs 7 at its lower end, which pass through the holes 6, receiving the ends of the bar between them. Pivot pins 8 pass through each pair of lugs at the adjacent 75 ends of the bar, so that the legs are secured to the bar; but are free to move away from and toward each other to the required extent.

The legs 2 are both widened at their upper ends as indicated at 9, and these ends are 80 curved transversely and provided with cross grooves 10 to receive the flange 11 of the cone-shaped top 4 of the tube. The widened ends 9 are curved on their opposed or inner faces so as to fit the circumference of the tube; and 85 on their remaining or outer faces they have transverse projections 12 which are engaged by the rim 13 of the cover 3. This rim has spring parts 14 which grip the tops of the legs 2 firmly, and to attach the stand to the tube one moves the legs 2 together until the flange 11 enters the grooves 10; and then 90 forces the cover 3 against the end of the tube and the tops of the legs; pressing the springy parts 14 over the projections 12. The stand thus holds the tube snugly.

I show the cover 3 with a bearing post 15 to which an arm 16 is pivotally attached by means of a screw 17 in the upper end of this post. This arm causes a valve cap 18 thereon 100

to close the upper end of the cover which terminates in a nozzle 19 in line with the neck 20 of the tube. The bearing 15 will carry a stop 21 to limit the movement of the arm 5 when the cap 18 is in position to close the nozzle 19.

The legs 2 at their lower ends have recesses 22 which may be between the lugs 7 to receive the extremities of the bottom 23 of 10 the tube. Hence the tube is positively engaged at both ends when the stand receives it. At the lower ends the arms may also be provided with expanded portions 24 larger than the openings 6, so that the outward 15 movement of the legs is effectively limited.

While I have shown a cover member 3 for holding the upper ends of the legs 2 in position to grip the top of the tube, this cover is to be regarded mainly as a convenient means 20 for securing the tops of the legs in engagement with the tube. Instead of the cover a ring which may have a conical portion to rest upon the top of the tube, and a flange or rim similar to the rim 13 with spring portions 14, 25 may be used. I may also utilize similarly a ring which goes around the top of the tube and the ends 9 of the legs 2 below the projections 12. Likewise a ring might be employed which slides up and down on the legs 2, this 30 ring to be pivotally attached to a sleeve which encircles one leg so as to be permanently connected to this leg; and the ring may be slipped upward and swung past the upper end of the other leg, whenever the legs are to 35 be released and the tube dismounted. Also catches might be mounted on the base to engage the legs and make them grip the tube; or a pivoted bar might be secured to one leg to be engaged by a suitable part on the other 40 to hold the legs in gripping position.

The legs 2 are made extensible by forming them each with an upper section 25, and a lower section 26, which has a slotted sleeve 27 receiving the upper section. The latter carries a pin 28 which engages the slot in the sleeve. The legs thus enable the stand to fit tubes of different lengths.

It will be noted from Figure 2, that the lower end of the tube engages the lower ends 50 of the legs and is held in position thereby.

I claim:

1. A stand for a collapsible tube having a body and a rigid top with a peripheral bead-flange, the stand comprising a base, legs supported at their lower ends to the base, the legs being shaped at their upper ends to engage the flanged top of the tube, and means at the upper ends of the legs to hold the legs in engaging position.

60 2. A stand or holder for a tube having a body and a flanged top, the stand comprising a base, legs supported at their lower ends to said base, the legs being shaped at their upper ends to engage the tube at its flanged top, 65 means engageable with said legs at the top

to hold the legs in engaging position, and a valve cap pivoted to said means to control the discharge of the contents of the tube.

3. A stand or holder for a tube having a body with a flanged top, the stand comprising a base, said base being hollow at its underside, a bar fixed to the base on said side, there being openings in the base at the ends of the bar, legs having lugs at their lower ends projecting through said openings and receiving the ends of the bar and pivoted thereto, the upper ends of the legs being shaped to engage the tube at the flanged top, and means for holding said legs in engaging position.

70

75

80

4. A stand or holder for a collapsible tube having a body and a flanged top, the stand comprising a base hollow on its underside, a transverse bar on the base secured to said side, the base having openings in its ends adjacent the ends of the bar, arms terminating at their lower ends in lugs which enter said openings and receive the ends of the bar between them and are pivoted thereto, stops carried by the lower ends of the bars above the base to engage the base and limit the movement of the arms away from each other, the upper ends of said arms being shaped to engage the tube at the flanged top, and means associated with said arms to hold them in gripping position.

85

90

95

5. A stand for a collapsible tube having a body with a flanged top, the stand comprising a base, arms pivotally connected at their lower ends to the base, the upper ends of said arms having widened portions which are curved transversely on the opposed faces of said ends, said faces having transverse grooves therein to receive the flanged top, and projections on the lower portions of said arms to serve as stops to limit the outward movement of the arms.

100

105

6. A stand for a collapsible tube having a body and rigid top with a peripheral bead-flange, the stand comprising legs and a base, the legs being supported at their lower ends to the base and shaped at their upper ends to engage the flanged top of the tube, said legs being lengthwise extensible to allow adjustment according to the length of the tube, and means for holding the legs in position to grip the flanged top of the tube.

110

115

7. A stand for a collapsible tube having a flanged top, the stand comprising a base, legs hinged thereto, each leg comprising a lower section with a sleeve, an upper section having pin-and-slot engagement with said sleeve, the legs being adapted to grip the flanged top of the tube between them and means for holding said legs in gripping position.

120

8. A stand for a tube comprising a collapsible body and a flanged top, the stand comprising legs to engage the flanged top, the legs having transverse openings for receiving therein the extremities of the bottom of the

130

tube, and means for holding the legs in engaging position.

9. A stand for a collapsible tube having a body and rigid top with a peripheral bead-flange, the stand comprising a base, legs supported by the base, the upper ends of the legs being provided with portions for lapping under the bead-flange whereby to support the tube by the legs.

10. A stand for a collapsible tube having a body and rigid top with a peripheral bead-flange, the stand comprising a base, legs supported by the base, one of the legs being adjustable relatively to the other, the upper ends of the legs being provided with portions for lapping under the bead-flange whereby to support the tube by the legs, and means for holding the upper ends of the legs firmly to the bead-flange.

20 In testimony that I claim the foregoing as my invention, I have signed my name hereto.

FRANK WOLF.
